By his attorney.

UNITED STATES PATENT OFFICE.

WILLIAM L. LANGE, OF NEW YORK, N. Y.

BANJO.

1,348,652.

Specification of Letters Patent. Patented Aug. 3, 1920.

Application filed April 30, 1919. Serial No. 293,832.

To all whom it may concern:

Be it known that I, WILLIAM L. LANGE, a citizen of the United States, residing in New York city, in the county of New York and State of New York, have invented certain new and useful Improvements in Banjos, of which the following is a specification.

This invention relates to musical instruments, such as the banjo, phonograph and 10 the like, and other apparatus in which vibrations are set up by vibrating diaphragms.

An object of the invention is to provide, in a device of this kind, an arrangement whereby lateral exits for the sound waves, 15 in addition to the ordinary exit, are provided permitting the egress of the waves without muffling.

Another object is to provide a suitable resonating chamber in which the sounds coming from the instrument are controlled.

Other objects of the invention will appear as the description proceeds; and various changes in the constructions described may be made without departing from the scope 25 of the invention as claimed.

In the accompanying drawing,

Figure 1 is a face view of a banjo to which my invention is applied;

Fig. 2 is a central vertical sectional view, 30 partly in elevation, of the device shown in Fig. 1;

Fig. 3 is a fragmental sectional view, on a larger scale, showing details of the invention;

Fig. 4 is a perspective view of a detail;

Fig. 5 is an enlarged fragmental vertical sectional view showing the path of the sound waves through the lateral exits and the amplifying tone chamber;

Fig. 6 a fragmental plan view showing the formation of the tone chamber;

Fig. 7 is a central vertical sectional view of a phonograph sound box embodying my invention; and

Fig. 8 is a face view of the sound box.

Referring to Figs. 1 to 4, my invention is shown applied to a banjo 10 comprising a rim 11 provided at its upper and outer edge with a bevel face 12 (Fig. 3), terminating at its lower part in an annular shoulder 13, said rim forming the interior chamber of the banjo. Upon the upper edge of the rim there are a plurality of vertically and radially disposed spacing 55 plates 15 provided with a horizontal lower edge engaging said shoulder 13, and with

an inclined intermediate edge engaging said bevel face 12. At the upper part of each spacing plate there is provided an inwardly pointing spacing extension 16, engaging 60 over the upper face of the rim, and provided with a downwardly and outwardly pointing projection 17 engaging in the frame rim for holding the spacing plate in place.

Arranged around the lower part of the outer face of the rim are a plurality of tension lugs or brackets 20, each provided with a bore 21 passing vertically therethrough. The lugs or brackets are held in place by a 70 plurality of bolts 22 passing through the rim and provided with threaded outer ends having threaded engagement with said lugs.

The spacing plates 15, project somewhat from the outer face of the rim, and are surrounded by a hoop 24, which has its lower edge resting upon the lugs 20 and its upper edge projecting above the spacing plates and rounded as at 25 (Figs. 3 and 5).

Resting upon the upper edge of said extension 16, is a steel spacing ring 27 of circular cross-section. Stretched across said ring and the upper edge of said tone hoop is a vellum of parchment membrane or diaphragm head 28 having its peripheral portion 29 down-turned and terminating in a flesh ring 30 surrounding the outer face of the hoop 24. A straining hoop 33 is placed around said down-turned portion and rests upon the flesh ring.

Each of the spacing plates 15 is provided with an aperture 15', which aperture may be of any suitable shape instead of circular, the spaces between the plates affording passages for sound from the interior of the 95 banjo, and the apertures 15' affording means for preventing diffraction of sound by the spacing plates during the passage of sound from the interior of the banjo.

In order to hold the straining hoop in 100 straining position, there are provided straining hook rods 35, each having an upper end-hook 36 disposed over the upper edge of the rim and engaging in a groove 37 therein. The lower end of the straining rod is threaded and passes through said bore 21, and is engaged by a nut 38 for tightening the straining rod.

The finger board 42, the bridge 43, and the tail piece 44 of the banjo form no part of 110 the present invention, except as means for providing vibrations of the diaphragm head.

In use the banjo is played upon as is an ordinary banjo. As is well-known, a banjo is usually held in the lap so as to close the lower opening of the chamber formed by the rim, thus partially muffling the sound of the banjo. With the banjo herein described, the sounds formed by the vibration of the diaphragm head, find outlet from the interior of the banjo, not only in the ordinary way, but also through the space formed between the spacing ring 28 and the rim; and the sound thus passing out passes also through the resonating chamber 48, formed between the hoop 24 and the outer face of the rim, and thence through the open bottom or outlet of the resonating chamber to the outer air.

The apparatus above described may be used with many and various kinds of instruments; for instance, a drum in which case the drum housing corresponds to the frame rim 11 of the banjo; and the tensioning and diaphragm supporting mechanism above described is merely repeated at both edges of the drum housing, as indicated by the dotted lines at the lower part of Fig. 2.

My invention may be also used in connection with the diaphragm of a phonograph, as shown in Figs. 7 and 8, in which the housing 60 is formed with a neck 61 for attachment to the tone arm of the phonograph, and also with an outer ring 62 and an inner spacing ring 63 supported by spacing pillars 64 integral with said ring 63 and with the inner part of the housing 60. The space between the tone rim 62 and the pillars 64 forms what may be termed a resonating chamber communicating with the interior of the neck 61, through passages 69. The diaphragm 70 is stretched across the outer face of the spacing ring 63, and has its free edge secured to a strain ring 72 clamped in grooves 73 and 74 provided respectively in the edge of said outer ring 62, and the inner face of a clamping ring 76. The ring 76 is provided with a threaded flange 77 having threaded engagements with threads on the periphery of the outer ring 62.

The diaphragm 70 is vibrated by the usual stylus bar 78, and the sound thus generated passes through the passages 64 into the resonating chamber 68, and thence through the passages 69 into the neck 61, which passages 69 afford means for preventing diffraction of sound in passing into the neck 61.

I claim:

1. In a musical instrument of the character described, in combination, an interior chamber; a resonating chamber; means for causing vibrations in the interior chamber; and means appurtenant to the resonating chamber provided with apertures therethrough for passage through the apertures of the sound caused by said vibrations and preventing diffraction of said sound.

2. In a musical instrument of the character described, in combination, an interior chamber; means for causing vibrations in the interior chamber; a resonating chamber; and means provided with apertures therethrough for passage through the apertures of the sound caused by said vibrations and preventing diffraction of said sound; said means being arranged transversely to the line of passage in the resonating chamber of said sound.

3. In a musical instrument of the character described, in combination, an interior chamber; means for causing vibrations in the interior chamber; a resonating chamber; and spacing means provided with apertures therethrough for passage through the apertures of the sound caused by said vibrations and preventing diffraction of said sound.

4. In a musical instrument of the character described, in combination, an interior chamber; means for causing vibrations in the interior chamber; a resonating chamber; and spacing means provided with apertures therethrough for passage through the apertures of the sound caused by said vibrations and preventing diffraction of said sound; said means being arranged transversely to the line of passage in the resonating chamber.

5. In a musical instrument of the character described, in combination, an interior chamber; means for causing vibrations in the interior chamber; means for outlet to the outer air for the sound caused by said vibrations; and means located between the interior chamber and said means for outlet provided with apertures therethrough for passage through the apertures of the sound caused by said vibrations and preventing diffraction of said sound.

6. In a musical instrument of the character described, in combination, an interior chamber; means for causing vibrations in the interior chamber; a resonating chamber; means for outlet to the outer air for the sound caused by said vibrations; and means located between the interior chamber and said means for outlet provided with apertures therethrough for passage through the apertures of the sound caused by said vibrations and preventing diffraction of said sound; said means being arranged transversely to the line of passage in the resonating chamber of said sound.

7. In a musical instrument of the character described, in combination, an interior chamber, a frame around the interior chamber forming a resonating chamber; means for causing vibrations in the interior chamber; and means appurtenant to the resonating chamber provided with apertures therethrough for passage through the apertures of the sound caused by said vibrations and preventing diffraction of said sound.

8. In a musical instrument of the character described, in combination, an interior chamber, a frame around the interior chamber forming a resonating chamber; means for causing vibration in the interior chamber; and means provided with apertures therethrough for passage through the apertures of the sound caused by said vibrations and preventing diffraction of said sound; 5 said means being arranged transversely to the line of passage in the resonating chamber of said sound.
9. In a musical instrument of the character described, in combination, an interior chamber; a frame around the interior chamber forming a resonating chamber; means for causing vibrations in the interior chamber; and spacing means provided with apertures therethrough for passage through the 10 apertures of the sound caused by said vibrations and preventing diffraction of said sound.
10. In a musical instrument of the character described, in combination, an interior chamber; a frame around the interior chamber forming a resonating chamber; means for causing vibrations in the interior chamber; and spacing means provided with apertures therethrough for passage through the 15 apertures of the sound caused by said vibrations and preventing diffraction of said sound; said spacing means being arranged transversely to the line of passage in the resonating chamber of said sound.
11. In a musical instrument of the character described, in combination, an interior chamber; a frame around the interior chamber forming a resonating chamber; a diaphragm strained over the interior chamber; 20 means for vibrating the diaphragm; and means provided with apertures therethrough for passage through the apertures of the sound caused by vibrating said diaphragm and preventing diffraction of said sound; 25 said means being arranged transversely to the line of passage in the resonating chamber of said sound.
12. In a musical instrument of the character described, in combination, an interior chamber; a frame around the interior chamber forming a resonating chamber; a diaphragm strained over the interior chamber; means for vibrating the diaphragm; and spacing means provided with apertures 30 therethrough for passage through the apertures of the sound caused by vibrating said diaphragm and preventing diffraction of said sound; said spacing means being arranged transversely to the line of passage in the resonating chamber of said sound.
13. In a musical instrument of the character described, in combination with a banjo, an exterior frame of the banjo; a frame around said banjo frame forming a resonating 35 chamber; means for supporting said
- resonating chamber frame around said banjo frame; a diaphragm strained over said banjo frame and over said resonating chamber frame; means for straining said diaphragm over said banjo frame and over said resonating chamber frame, and for retaining the diaphragm in strained position; means for vibrating said diaphragm; and means for spacing said resonating chamber frame from 40 said banjo frame; said means for spacing being provided with apertures therethrough for passage through the apertures of sound caused by vibrating said diaphragm and preventing diffraction of said sound.
14. In a musical instrument of the character described, in combination with a banjo, an exterior frame of the banjo; a frame around said banjo frame forming a resonating chamber; means for supporting said resonating chamber frame around said banjo frame; a diaphragm strained over said banjo frame and over said resonating chamber frame; means for straining said diaphragm over said banjo frame and over said resonating chamber frame, and for retaining the diaphragm in strained position; means for vibrating said diaphragm; and plates for spacing said resonating chamber frame from said banjo frame; said plates being provided with apertures therethrough for passage through the apertures of sound caused by vibrating said diaphragm and preventing diffraction of said sound.
15. In a musical instrument of the character described, the combination of a rim; 50 spacing plates disposed around said rim and each provided with a spacing extension secured over the upper face of said rim; a pressure ring resting upon said extensions; a diaphragm head stretched across said rim; and means for holding the edge of the head strained and spaced from said rim.
16. In a musical instrument of the class described, the combination of a rim; spacing plates disposed radially around said rim, 55 each plate being provided with a spacing extension secured over the upper face of said rim; a plurality of tensioning lugs around the rim; a hoop around and projecting above said spacing plates and resting upon said lugs; a pressure ring upon said extensions; a diaphragm head stretched across said ring and hoop and terminating in a flesh ring surrounding said hoop; a straining hoop resting upon said flesh ring; and 60 straining rods connecting said hoop and lugs.
17. In a musical instrument of the character described, the combination of a rim; spacing plates disposed vertically and radially around and projecting outwardly from said rim, each plate being provided at the upper part with an inward spacing extension engaging over the upper face of said rim and provided with a downwardly and 65

outwardly pointed projection from the extension engaging in said rim for holding the spacing plate in place; a plurality of tensioning lugs disposed around the outer face 6 of the rim; a hoop having its lower edge resting upon said lugs, and having its inner face engaging and held spaced from the rim by the outer edge of said spacing plates and its upper edge projecting above said spacing 10 plates; a pressure ring resting upon said spacing extensions; a head stretched across said ring and the upper edge of said hoop, and having its peripheral portion down-turned and terminating in a flesh ring surrounding 15 the outer face of said hoop; a straining hoop around said down-turned portion and resting upon said flesh ring; and straining rods secured to said lugs and having hooks disposed over said straining hoop.

18. In a musical instrument of the character described, the combination of a rim provided at its upper and outer edge with a beveled face terminating at its lower part with an annular shoulder; a plurality of spacing plates disposed vertically and radially around and projecting outwardly from said rim, each plate being provided with a horizontal lower face engaging said shoulder, and provided with an inclined intermediate face engaging said beveled face, and provided at the upper part with an inward spacing extension engaging over the upper face of said rim, and provided with a

downward and outward projection from the extension engaging in said rim for holding the spacing plate in place; a plurality of tensioning lugs disposed around the outer face of the rim and each provided with a vertical hook-rod bore; a plurality of bolts passing radially through said rim in the lower part thereof and having threaded engagement with said lugs for holding the lugs to the rim; a hoop having its lower edge resting upon said lugs, and having its inner face held spaced from the rim by the outer edge of said spacing plates, and its upper edge slightly rounded and projecting above said spacing plates; a pressure ring of circular cross-section resting upon the upper edge of said spacing extensions; a diaphragm head stretching across said rim and the upper edge of said hoop, and having its peripheral portion down-turned and terminating in a flesh ring surrounding the outer face of said hoop; a straining hoop placed around said down-turned portion and resting upon said flesh ring; straining hook-rods having their lower threaded ends passed through said bores and their hooks disposed over said straining hoop; and nuts secured at the lower ends of said straining rods.

WILLIAM L. LANGE.
